UNITED STATES PATENT OFFICE.

ALBERT C. MURPHY, OF NEW YORK, N. Y.

DUMPING-CAR.

1,224,404.

Specification of Letters Patent.

Patented May 1, 1917.

Application filed July 3, 1914. Serial No. 848,728.

To all whom it may concern:

Be it known that I, ALBERT C. MURPHY, a citizen of the United States, and resident of New York, county of New York, and 5 State of New York, have invented an Improvement in Dumping-Cars, of which the following is a specification.

My invention has for its object the construction of a dumping car which may be 10 operated from one or both ends of the car for dumping the load to either side of the track, and providing automatic side doors for the body for releasing the contents and guiding them to a distance from the road 15 bed when the body has been tilted into a discharging position.

My invention consists of certain constructions which are fully described hereinafter and more particularly defined in the claims, 20 and these will be better understood by reference to the drawings in which:

Figure 1 is a side elevation of a dumping car embodying my improvements; Fig. 2 is a plan view of the same with the tabs over 25 the end platforms removed; Fig. 3 is an enlarged side elevation of the left hand portion of Fig. 1 showing the structure more in detail; Fig. 4 is a transverse section of the vehicle on line $x-x$ of Fig. 3; Fig. 5 is a transverse sectional elevation on line $y-y$ of Fig. 3; Fig. 6 is a cross sectional view illustrating the details of the locking device or latch for holding the doors closed; Fig. 7 is a sectional elevation on line $t-t$ 30 of Fig. 3 showing the means for operating the car body; and Fig. 8 is a side elevation with a portion in section of the operating means for tilting the body.

2 is a girder frame extending throughout 40 the length of the car and constituting the main frame of the car. Near each end this main frame is provided with the pivot block 3^a to which the trucks 4 (diagrammatically indicated) are pivoted and which may be 45 of any suitable construction. Furthermore, adjacent to the pivot blocks the main frame is provided with lateral extensions 2^a at each side and which have the shoe portions 3 adapted to rest upon the truck frame, the 50 said parts 2^a, 3 and 3^a being in connection with the girder frame 2 constituting the bolster of the main frame for transmitting the weight of the car upon the truck frame. Each end of the main frame 2 is provided 55 with a platform 5 preferably housed in by a cap 6 in which the workmen may find

shelter during transportation and when operating the power transmitting mechanism 25, employed in connection with the tilting of the car body 7. Preferably there is one 60 of these platforms and operative mechanism at each end of the car, but this is not essential as the car body may be operated wholly from one end of the car if so desired.

The car body is preferably formed of a 65 longitudinal box body of sheet metal having side openings for the discharge of the contents, said openings being normally closed by hinged doors 9, the latter being hinged at 10 to the lower sides of the body 70 and detachably locked in closed position at their upper ends by latches or locks 11 carried upon and operated by rock shafts 12. These rock shafts are suitably journaled in bearings carried upon the top side 75 rails 7^a of the body, and as shown in Fig. 6 the latches 11 are loosely hinged upon the shaft 12 and are provided with elongated slots 11^a into which project studs 12^a of the shaft, said construction being such that the 80 latch 11 may be lifted by hand into the dotted position (Fig. 6) when closing the door without the rocking shaft 12, whereby each door may be closed by the workmen without having to manipulate the car body. 85 When the doors are to be automatically opened the rock shafts 12 rock, and this through the stud 12^a turns the latch 11 into the dotted position to release the door 9 and allow it to fall as indicated in dotted lines in Figs. 4 and 5. There may be a 90 number of doors 9 on each side of the body according to its length, so as to reduce the amount of weight which would have to be lifted by the workmen in closing the doors 95 at any one time. When the doors drop into the open position they are held in oblique relation by means of chains 9^a and springs 9^b, the latter being connected to the top side rails 7^a and the former connected with the 100 doors near their free ends. When the door drops by gravity after being released its inertia on assuming the position indicated in dotted lines is taken up by the elasticity of the springs 9^b and in its open position acts as a chute or guiding apron for guiding the contents of the load of the body to a distance away from the track upon which the vehicle runs. The body 7 is provided on its under side with rockers 17 which 105 rock upon the transverse beds 18, the rockers 17 being preferably provided with teeth and

the beds with apertures for engagement by the teeth and which prevent lateral abnormal displacement of the rocker upon the bed. The rockers are so made that as the 5 body tilts to discharge, the center of gravity of the body and the load travels transversely to the central line of the truck frame so that the load is normally above the point of contact of the rocker with 10 the bed.

To operate the latches or locks 11 automatically to release the doors when the body is tilted into its oblique position, I employ the following mechanism. Secured to the 15 end of the rock shaft 12 is an arm 13 and to the free end of this arm is hinged a rod 14, said rod telescoping with a tube 15, the lower end of which is hinged at 16 to the bolster of the truck frame as clearly indicated in 20 Fig. 4. Similar mechanism is arranged to operate on the other rock shaft for controlling the doors on the opposite side of the body as indicated in dotted lines in Fig. 4, said mechanism being arranged at the distant end of the body. By this mechanism it is evident that when the body is tilted the rising side of the body will draw the rod 14 upward to a greater or less extent out of the tube 15 without rocking the rock shaft, but 25 on the descending side of the body the lower end of the rod 14 will reach the bottom of the hole in the tube 15 and the further depression of the body will cause the arm 13 to be locked relative to the body and this will 30 impart a rocking motion to the shaft 12 and the latches or locks 11 to raise them and liberate the door as indicated in dotted lines. When the body is returned to its horizontal position the locks or latches 11 will have 35 turned to their normal positions shown in Figs. 4 and 5 and at this time the doors 9 may be lifted and moved back into closed position, but to enable this to be done the locks and latches 11 must be raised to permit 40 passage of the free ends of the doors and this is 45 permitted by having the locks or latches free to be lifted on the rock shaft 12 by hand manipulation as heretofore described in connection with Fig. 6.

50 The body, as heretofore stated, is a box shaped frame preferably strengthened by suitable longitudinal girders 7^b, 7^c and 7^d (Fig. 5), the transverse rockers 17 being securely positioned upon the central girder 7^d 55 and between the two longitudinal girders 7^b. Moreover, the body is reinforced transversely by means of transverse girders 8 which, as shown in Fig. 1, are three in number and these extend preferably about half 60 way up throughout the main portion of their length and wholly up to the upper portion of the body at each of their lateral ends, said construction being more fully illustrated in Fig. 5. These transverse girders act as 65visions to properly guide the load in dis-

charging, and at the same time at each end provide a closure between the adjacent edges of the doors. By employing these divisions 8 a portion only of the contents may be discharged if so desired, but in this event it 70 would be necessary to release the side door 9 of the particular compartment from which the contents was to be discharged.

The following mechanism is employed to rock the body upon the longitudinal girder 75 frame, and this mechanism is preferably duplicated on each side of the axis of oscillation and adapted to be operated from both ends of the car. At each side of the longitudinal frame 2 and journaled in the lateral 80 extensions 2^a thereof are the longitudinal shafts 19, said shafts extending to the platforms at each end of the girder frame and provided with one or more pinions 20, preferably held in position within the lateral extensions 2^a of the girder frame. These pinions engage racks 21 which are hinged at their upper ends at 22 to the tilting body 85 respectively at each side of the transverse rockers. These racks 21 are preferably held 90 into engaging position with the pinions by the guide rollers 23 which are also journaled in the lateral extensions 18 of the girder frame. These lateral extensions 18 of the girder frame are preferably reinforced by 95 the transverse girders 2^b which extend the full width of the girder frame. At one end of each shaft 19 is a sprocket wheel 24 and at the other end is a lock wheel 31 having a notch 32 in its periphery. These sprocket 100 wheels and locking wheels are so arranged that there is one of each under each of the platforms 5 so that the car body may be tilted by the shaft having the sprocket wheel under the platform at which the operator 105 stands, and the car body may be locked by a locking lever 33 engaging the notch in the locking wheel 31 under the said platform on the other of the shafts 19. This locking of 110 the car body may be employed more particularly when the car body is in the horizontal position during transportation, but it may be also temporarily locked when the body is tilted if so desired. As shown in Figs. 7 and 8 the locking lever 33 in its locking position has the handle end raised and supported over a lug 35 on a spring arm 34 which is bolted to the main frame 26 of the power applying devices which are employed 115 to tilt the body. Assuming the parts are in the position shown in Figs. 7 and 8 with the car body horizontally positioned for transportation, and it should be desired to tilt the body for discharging the load at the place of destination, the first operation 120 would be to pull the upper end of the spring arm 34 outward to release the lever 33 and permit it to drop into the position indicated in dotted lines in Fig. 7 in which it is disengaged from the locking wheel 31. The car 125 130

body may then be tilted by rotating the shaft 19 having the sprocket wheel and which preferably operates upon the rack 21 to push upward, it being more desirable that 5 the tilting shall be produced by a thrust rather than by a pull. I, however, do not restrict myself in this respect.

It will now be seen that if the hand wheel 29 be rotated the speed reducing gears 28 10 will rotate the sprocket pinion 27 and this, through the sprocket chain 30, is made to rotate the sprocket wheel 24 and its shaft 19 to tilt the body. Owing to the tendency of the loaded body to return to its normal 15 position it is desirable that the hand wheel and pinion shall be held against rotating backward, and yet have provision when desired for rotation in either direction. To provide such means I prefer to employ a 20 detent wheel 36 which may be varied much like an ordinary gear. Engaging with this detent wheel 36 is a pivoted pawl device 37 which has engaging teeth arranged to operate in both directions. Pivoted to the main 25 frame 26 above the pawl is an arm 38 and to this arm is connected a spring 39 whose other end is connected with the pawl 37 above its pivotal point. When the arm 38 is thrown into the position shown in Fig. 7 30 the spring pulls the pawl into engagement at the right hand side of the detent wheel and it will now be seen that the said wheel may be rotated to the right like the hands of a watch, but cannot rotate in the opposite direction. If, however, the arm 38 is thrown over to the left of the main frame 26, then the other side of the pawl comes into contact with the detent wheel and the hand wheel then may rotate freely to the 35 left or in a reverse direction to the hands of a watch and will be locked against rotation in the other direction. It is therefore possible for the operator to throw this arm 38 in either direction according to whether 40 the wheel is required to rotate to the right or to the left to suit the particular tilting of the car body which is required. It is to be kept in mind that in the tilting of the body one of the shafts 19 rotates in one direction and the other in the opposite direction so that if an operator were to stand in front of the hand wheels in each of the two 45 cabs, the two hand wheels will necessarily rotate in opposite directions, and if the car 50 is to be operated solely from one end, then the operator must first disengage the locking lever 33 at the opposite end of the car and also throw the arm 38 at that end so that it will permit the freedom of movement of the hand wheel, and then he may 55 operate the car body from the opposite end of the car under perfect control. If the load is very heavy and it is desirable to operate the tilting from each end of the 60 car, then an operator will be on each plat-

form and will accordingly manipulate the parts to coöperate in the operation of the body. It will thus be seen that the body may be tilted or rocked from each end of the car, but I do not restrict myself to this 70 use of double power mechanism and double locking mechanism as it is manifest that if desired the car may have only one operating platform and one set of operating mechanism for the two shafts, one of which 75 would act as a locking shaft and the other as a tilting shaft. It is also manifest that with the two platforms the entire operation of the vehicle body may be conducted with the use of one shaft and the pinion and rack 80 connections, as in this case this shaft may be locked in by the mechanism at one end and may be operated when unlocked by the mechanism at the other end, these variations being within the capacity of the engineer in designing and using the car. 85

It is also evident that while I have shown no means for operating the car body, any of the usual and well known power devices may be employed in lieu thereof if so desired, but for ordinary purposes hand operated means is found to be entirely satisfactory. 90

In the tilting of the body upon the main girder frame the rockers and beds are so 95 constructed that the center of gravity of the loaded body moves laterally commensurate with the shifting of the axis of oscillation between the rockers and beds so that at all times a minimum power will be sufficient 100 to rock the car body. The means of pivoting and rocking the car body may, however, be varied without deviating from the essential requirements of the invention. 105

I have shown my improved car construction in the form which I have found well adapted for commercial requirements, but I do not restrict myself to the minor details as these may be varied in many ways without departing from the spirit of the invention. 110

Any matters shown and described in this application relating to the tilting box body and the means for operating the same, and also to the rocker means such as the limiting abutments therefor, and not claimed herein, form subject matter of my application Ser. No. 775,462, filed June 24, 1913; and neither do I make claim in this application to the box body having the intermediate transverse divisions and with side doors, as the same also has been claimed in my said application Ser. No. 775,462. 115 120

Having thus described my invention, what I claim as new and desire to protect 125 by Letters Patent is:

1. In a dumping car, the combination of a longitudinal car frame having a plurality of transverse rocker beds, a box body arranged above the longitudinal frame and having a 130

- plurality of rockers on its under side adapted to the beds said body provided with discharge apertures at its sides, doors hinged to the sides of the body to normally close the discharge apertures, a longitudinal shaft journaled on the longitudinal car frame and extending to the end portion thereof and located wholly below and independent of the box body, non-flexible mechanical connections between the shaft and the body for tilting it in either direction, a platform at the end of the car, and means independent of the body located at the end of the car frame adjacent to the platform for rotating the longitudinal shaft whereby the box body may be rocked in either direction to discharge from either side of the car.
2. In a dumping car, the combination of a longitudinal car frame having a plurality of transverse rocker beds, a box body arranged above the longitudinal frame and having a plurality of rockers on its under side adapted to the beds, said body provided with discharge apertures at its sides, doors hinged to the sides of the body to normally close the discharge apertures, a longitudinal shaft journaled on the longitudinal car frame and extending to the end portion thereof and located wholly below and independent of the box body, non-flexible mechanical connections between the shaft and the body for tilting it in either direction, a platform at the end of the car, means independent of the body located at the end of the car frame adjacent to the platform for rotating the longitudinal shaft whereby the box body may be rocked in either direction to discharge from either side of the car, and unitary means for locking the longitudinal shaft against rotation in either and both directions at the will of the operator.
3. In a dumping car, the combination of a longitudinal car frame having a plurality of transversely arranged rocker beds and a platform at each end, a box body arranged above the longitudinal frame and having a plurality of rockers on its under side adapted to the beds, said body provided with discharge doors on both of its sides, two longitudinal shafts journaled on the longitudinal car frame independent of the body and one of said shafts extending to one of the platforms and the other extending to the other platform, mechanical connections between car body and the respective shafts whereby the rotation of each of the shafts may tilt the box body in either direction so as to discharge from either side of the car, and power applying means arranged at each platform for rotating the respective shafts.
4. In a dumping car, the combination of a car frame having a platform at one end and a plurality of transverse rocker beds, with a box body arranged above the car frame and having a plurality of rockers on its under side adapted to the beds whereby the body may be rocked to incline said body and lower the dumping side thereof to either side of the car frame, side doors hinged to said body, two longitudinal shafts journaled in the car frame respectively upon each side of the rocker beds and the ends of said shafts extending to the platform end of the car frame, connecting means between the said shafts and the body upon opposite sides of the rockers for oscillating the body, mechanical means adjacent to the platform for rotating one of the longitudinal shafts, and means also adjacent to the platform for locking the other longitudinal shaft against rotation in either and both directions at the will of the operator.
5. In a dumping car, the combination of a car frame having a platform at one end and a plurality of transverse rocker beds, with a box body arranged above the car frame and having a plurality of rockers on its under side adapted to the beds whereby the body may be rocked to incline said body and lower the dumping side thereof to either side of the car frame, side doors hinged to said body, two longitudinal shafts journaled in the car frame respectively upon each side of the rocker beds and the ends of said shafts extending to the platform end of the car frame, connecting means between the said shafts and the body upon opposite sides of the rockers for oscillating the body, mechanical means adjacent to the platform for rotating one of the longitudinal shafts, and means also adjacent to the platform for locking the other longitudinal shaft against rotation in either and both directions at the will of the operator.
6. In a dumping car, the combination of a car frame having a platform at one end and a plurality of transverse rocker beds, with a box body arranged above the car frame and having a plurality of rockers on its under side adapted to the beds whereby the body may be rocked to incline said body and lower the dumping side thereof to either side of the car frame, side doors hinged to said body, two longitudinal shafts journaled in the car frame respectively upon each side of the rocker beds and the ends of said shafts extending to the platform end of the car frame, connecting means between the said shafts and the body upon opposite sides of the rockers for oscillating the body, mechanical means adjacent to the platform for rotating one of the longitudinal shafts, and means also adjacent to the platform for locking the other longitudinal shaft against rotation in either and both directions at the will of the operator.

- one of the longitudinal shafts, means also adjacent to the platform for locking the other longitudinal shaft against rotation in either and both directions at the will of the 5 operator, and means in connection with the mechanical means for locking the shaft which is operated by the mechanical means against backward rotation when the body is tilted or being tilted.
- 10 7. In a dumping car, the combination of a longitudinal car frame having a plurality of transverse rocker beds, a box body arranged above the longitudinal frame and having a plurality of rockers on its under side adapted 15 to the beds, said body provided with discharge apertures at its sides, doors hinged to the sides of the body to normally close the discharge apertures, a longitudinal shaft journaled on the longitudinal car frame and 20 extending to the end portion thereof and located wholly below the box body, a platform at the end of the car, means at the end of the car frame adjacent to the platform for rotating the longitudinal shaft whereby the 25 box body may be rocked in either direction to discharge from either side of the car, means for locking the longitudinal shaft against rotation in either and both directions at the will of the operator during the trans- 30 portation of the car, and separate means for permitting the shaft to be rotated in one direction and held against rotation in the opposite direction when the box body is tilted or being tilted.
- 35 8. In a dumping car, the combination of a car frame having a platform at each end and a plurality of transversely arranged rocker beds intermediate of the platforms, a box body arranged above the bed and having a 40 plurality of rockers supported by the beds whereby the body may be rocked for discharging the contents thereof to either side of the car frame two longitudinal shafts journaled in the car frame and respectively 45 arranged below the body on each side of the beds and said shafts extending between the platforms, connecting means between the said shafts and the box body upon the opposite sides of the rocker support therefor 50 whereby an upward thrust or a downward pull may be exerted upon the body for tilting, mechanical means on each of the platforms for rotating a different one of the two shafts whereby the box body may be rocked from either end of the car, and means for locking the shafts against rotation in one direction when the box body is tilted or being tilted.
- 55 9. In a dumping car, the combination of a car frame having a platform at each end and a plurality of transversely arranged rocker beds intermediate of the platforms, a box body arranged above the bed and having a plurality of rockers supported by the beds 60 whereby the body may be rocked for dis- 65
- charging the contents thereof to either side of the car frame, two longitudinal shafts journaled in the car frame and respectively arranged below the body on each side of the beds and said shafts extending between the platforms, connecting means between the said shafts and the box body upon the opposite sides of the rocker support therefor 70 whereby an upward thrust or a downward pull may be exerted upon the body for tilting, mechanical means on each of the platforms for rotating a different one of the two shafts whereby the box body may be rocked from either end of the car, means for locking the shafts against rotation in one direction when the box body is tilted or being tilted.
- 75 10. In a dumping car, the combination of a longitudinal frame, a box body supported upon the longitudinal frame and arranged to be tilted to dump to either side thereof, doors hinged to the lower parts of the sides of the box body and adapted to open downward to guide the contents being discharged from the tilted body, separate flexible connecting means each having one end connected to a door and the other end to the upper part of the body for holding the doors in inclined position during the dumping operation said independent means each provided with a separate spring to take up the inertia of the falling door, and mechanical means for locking the doors in their closed positions.
- 80 11. In a dumping car, the combination of a longitudinal car frame, a box body supported upon the longitudinal frame so as to be tilted in either direction whereby the contents may be dumped to either side of the 85 car, two longitudinal shafts journaled in the longitudinal frame below the box body and on each side of its support and the ends of said shafts extending to one end of the longitudinal car frame, mechanical connections 90 between the shafts and the box body at each side of its support, a notched disk secured to the end of one of the longitudinal shafts, a sprocket wheel secured to the other of the longitudinal shafts, operable means arranged 95 at the end of the car frame for operating the sprocket wheel and holding it against rotation in one direction during the tilting of the body, and hand operating means also adjacent to the end of the car frame for locking and unlocking the notched disk.
- 100 12. In a dumping car, the combination of the longitudinal car frame having a plurality of transverse rocker beds and a platform at each end, a box body structure ar- 105
- 125
- 130

- ranged above the longitudinal frame and having a plurality of rockers on its under side adapted to the beds to freely rock thereon, said body structure provided with discharge doors on both of its sides, two parallel longitudinal shafts respectively journaled on the longitudinal car frame at opposite sides of the rocker beds and respectively extending in opposite directions to the platforms thereof, a mechanical connection between the respective longitudinal shafts and the box body structure at opposite sides of the rockers whereby the rotation of the shafts will rock the body structure upon the beds in both directions to dump to either side of the car as desired, means at one platform of the car frame for rotating one of the longitudinal shafts, and means at the other platform for rotating the other of the longitudinal shafts.
13. In a dumping car, the combination of the longitudinal car frame having a plurality of transverse rocker beds, a box body arranged above the longitudinal frame and having a plurality of rockers on its under side adapted to the beds said body provided with discharge doors on its sides, a longitudinal shaft journaled in fixed bearings on the longitudinal car frame independent of and below the body and extending to the end portion of the car frame, a mechanical connection between the longitudinal shaft and the box body whereby the rotation of the shaft will rock the body upon the beds, means at the end of the car frame independent of the body for rotating the longitudinal shaft in either direction, and separate manually controlled means for locking the longitudinal shaft against rotation in either and both directions at the will of the operator.
14. In a dumping car, the combination of the longitudinal car frame having a plurality of transverse rocker beds, a box body arranged above the longitudinal frame and having a plurality of rockers on its under

side adapted to the beds said body provided with discharge doors on its sides, a longitudinal shaft journaled on the longitudinal car frame and extending to the end portion thereof, a mechanical connection between the longitudinal shaft and the box body whereby the rotation of the shaft will rock the body upon the beds, and means at the end of the car frame for rotating the longitudinal shaft consisting of a sprocket wheel on the longitudinal shaft, a sprocket pinion arranged above the shaft on the car frame, a sprocket chain connecting the sprocket wheel and pinion, a hand wheel, power multiplying gearing between the hand wheel and the sprocket pinion, and locking means for locking the pinion and hand wheel against rotation when the box body is tilted.

15. In a dumping car, the combination of a longitudinal car frame having a plurality of transverse rocker beds and a platform at the end thereof, a box body structure arranged above the longitudinal frame and having a plurality of rockers on its under side adapted to the beds said body provided with discharge doors on both of its sides, a longitudinal shaft journaled in the longitudinal car frame and extending to the platform thereof, a mechanical connection between the longitudinal shaft and the box body whereby the rotation of the shaft in one direction will tilt the body to discharge to one side of the car and the rotation of the shaft in the opposite direction will tilt the body to discharge to the other side of the car, means at the car platform for rotating the shaft in either direction, and devices for locking the shaft against rotation to enable the body to be held in tilted position.

In testimony of which invention, I hereunto set my hand.

ALBERT C. MURPHY.
